UNITED STATES PATENT OFFICE

170,350

LAUNDRY DRIER

Howard L. Bourner, Nashville, Tenn., assignor to
Temco, Inc., Nashville, Tenn., a corporation of
Tennessee

Application November 26, 1952, Serial No. 22,458

Term of patent 14 years

(Cl. D49—1)

To all whom it may concern:

Be it known that I, Howard L. Bourner, a citizen of the United States of America, residing at the city of Nashville, county of Davidson, State of Tennessee, have invented a new, original, and ornamental Design for a Laundry Drier, of which the following is a specification, reference being had to the accompanying drawing, forming a part thereof, and wherein:

Figure 1 is a perspective view of a laundry drier showing my new design.

Figure 2 is a top plan view thereof.

Figure 3 is a front elevational view thereof.

Figure 4 is a right-hand side elevational view thereof.

I claim:

The ornamental design for a laundry drier, as shown.

HOWARD L. BOURNER.
